JAMES T. DOWDALL, OF OZONE PARK, NEW YORK, ASSIGNOR OF ONE-HALF TO JOHN T. KEVENNEY, OF BROOKLYN, NEW YORK

AUXILIARY FEED DEVICE FOR SEWING MACHINES

Application filed August 1, 1931. Serial No. 554,396.

This invention relates to sewing machines and more particularly to the feeding mechanism therefor, and has for one of its objects the provision of an auxiliary feeding device which will insure simultaneous, equal, and positive feed of all superposed layers of material that are being sewn together.

Another object of the invention is to provide an auxiliary material feeding device for sewing machines that is directly carried by the usual feeding mechanism, so that it may move therewith in proper timing relation and be actuated for passing the material against the toothed feed bar when said bar is raised into feeding position.

A further object of the invention is to provide a device of this nature that may be attached to the material feeding device of any sewing machine without materially changing the said machine.

Still another object of the invention is to provide a device of the character described that may readily be detached from the machine and one that will not interfere with the normal operation of the said machine when left attached thereto.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions,

one of which, for the purpose of illustration, is shown in the accompanying drawings, in which—

Figure 1 is a sectional view through the feeding mechanism of a sewing machine showing my invention as applied thereto.

Figure 2 is an end view thereof partly in section, looking from the left of Fig. 1.

Fig. 3, is a top plan view of the device with the needle plate partly broken away for the sake of clearness.

Fig. 4, is a detail view in perspective of the material gripping plate and

Fig. 5 is a similar view of the plate carrier.

It is a well known fact that when sewing through two or more plies of material by a sewing machine, the lowermost ply becomes gathered, due to the fact that it is in direct contact with the feed bar of the machine and is positively fed thereby, while the upper ply contacts with the presser foot which so far as feeding is concerned is relatively stationary, thereby slightly retarding the feeding of the said upper ply and causing a relative slippage or a relatively different rate of feeding speed or travel of the said plies.

In order to obviate this undesirable feature I have provided a gripper arm that travels with the feeding bar thereby eliminating any possible slippage between the said plies.

Referring now to the drawings in detail 10 indicates the frame of a sewing machine in which there is rotatably mounted a drive shaft 11 connected to the usual driving mechanism or source of power not shown.

The said shaft 11 carries the sewing hook 12 and eccentrics 13 and 14. Pivotaly mounted at 15 is a cradle 16 in which there is pivotally mounted a bifurcated lever 17, the fork portion 18 thereof straddling the eccentric 13. The material feeding bar 20 is secured to the said lever 17 by means of a screw 21. A second bifurcated lever 22 is pivotally connected to the lever 17 at 23 and straddles the eccentric 14, and is pivotally connected at 24 to a lever 25 swingingly mounted at 26.

Secured to the lever 17 by means of screws 30 is a block 31 carrying a pin or short shaft 32 upon which is pivotally mounted a plate

33 provided at the front thereof, with a material gripping finger 34 and at the rear thereof with an extension 35 having an opening 36 acting as an anchor for one end of a spring 37 which at its opposite end is anchored to an extension 38 on the carrier block 31. The said plate or the finger portion thereof is preferably made of resilient material. A strap or stop bracket 40 is secured by means 10 of a screw 41 to the top surface of the needle plate 42. This strap extends over the top of the bracket 33 as shown in Figs. 1, 2 and 3. The needle plate 42 is provided with a cutout 43 through which the carrier block 31 extends 15 and a second cutout 44 in which the feed bar 20 is guided.

The presser foot 45 is provided with a cutout 46 to accommodate the gripping finger 34 as well as the needle 47 carried by the 20 needle bar 48.

In the type of sewing machine illustrated the eccentric 13 raises the lever 17 together with the feed bar 20, and the eccentric 14 actuates the lever 22 to swing the said lever 17 and the feed bar to and fro for feeding 25 purposes.

It will therefore be seen that each time that the lever 17 and feed bar 20 is raised the carrier block 31 and the plate 33 will be raised therewith and that during this action the strap or bracket 40 will cause the said plate 33 to swing downwardly at the finger end and grip or press the material against the feed bar 20 and as the carrier block and plate 35 travel with the feed bar 20 no slippage is possible between any of the material plies. The resiliency of the finger 34 will compensate for any variations in the thickness of the materials sewn.

From the foregoing it will be seen that I have provided a simple and efficient auxiliary feed for sewing machines that will insure evenness in appearance of two or more plies of material sewn by the said machine by positively and simultaneously feeding all of the 45 said plies at a uniform rate of speed.

Having described my invention what I claim as new and desire to secure by Letters Patent is:

50 1. An auxiliary material feed mechanism for sewing machines comprising a reciprocative and elevatable support, a plate pivotally mounted thereon, a finger on the said plate, a stop engaging the said plate, and spring means for maintaining the plate against the stop.

60 2. In a sewing machine having a reciprocative and elevatable feed bar, a pivotally mounted gripping plate in operative engagement with the said feed bar, a stop for the said plate and a spring to maintain the said plate in engagement with the said stop.

65 3. In a sewing machine having a reciprocative and liftable lever, a material feeding bar thereon, a carrier on the lever, a plate pivot-

ally mounted on the carrier, a stop in operative engagement with the plate, a finger on the plate in operative relation to the feed bar and a spring exerting a tension on the plate for the purpose specified.

70 4. In a sewing machine, a movable lever, a feed bar carried thereby, a pivotally mounted gripping member on the lever and in operative engagement with the feed bar, a spring for the said gripping member, means for raising and reciprocating the lever and feed bar and a stop in engagement with the gripping member for deflecting same when the lever and feed bar are raised.

75 5. In a sewing machine, a movable feed bar, a pivotally mounted gripping member operatively connected to the feed bar to move therewith, a spring for the said gripping member, means for raising and reciprocating the said feed bar, and a stop for deflecting the 80 said gripping member when the feed bar is raised.

85 6. In combination with the material feeding mechanism of a sewing machine, an auxiliary feed therefor, comprising a pivotally mounted and depressible gripper arranged to move with the said feeding mechanism, and a stop to deflect the said gripper to grip the material when it is being fed.

90 In testimony whereof I hereunto affix my signature.

JAMES T. DOWDALL.
